ATTORNEY

UNITED STATES PATENT OFFICE

HENDERIKUS JACOBUS VERWAYEN, OF ASTORIA, LONG ISLAND, NEW YORK

DESIGN FOR A LAMP

Application filed June 26, 1930. Serial No. 36,188. Term of patent 3½ years.

To all whom it may concern:

Be it known that I, HENDERIKUS JACOBUS VERWAYEN, a subject of the Netherlands, residing at Astoria, L. I., in the county of Queens and State of New York, have invented a new and original and ornamental Design for Lamps, of which the following is a specification, reference being had to accompanying drawing, forming part thereof.

Fig 1 is a front view of a lamp showing my new design.

Fig. 2 is a side view thereof.

I claim:

The ornamental design for a lamp as shown.

HENDERIKUS J. VERWAYEN.
